(57) **CLAIM**

The ornamental design for a pillow as shown and described.

DESCRIPTION

FIG. 1 is a top front perspective view of a pillow in accordance with our new design;

FIG. 2 is a bottom rear perspective view thereof;

FIG. 3 is a top rear perspective view thereof;

FIG. 4 is a bottom front perspective view thereof;

FIG. 5 is a front view thereof;

FIG. 6 is a rear view thereof;

FIG. 7 is a right-side view thereof;

FIG. 8 is a left-side view thereof;

FIG. 9 is a top view thereof;

FIG. 10 is a bottom view thereof showing the overhang of the upper surface; and,

FIG. 11 is an exploded top front perspective view thereof. The broken lines in the figures illustrate perforations in the pillow material and form part of the claimed invention.

1 Claim, 11 Drawing Sheets
